EXTENSIBLE VACUUM CLEANER CONDUIT

Axel Albert Forsberg, Stockholm, Sweden, assignor to Electrolux Corporation, Dover, Del., a corporation of Delaware

Application March 26, 1937, Serial No. 133,117
In Germany March 28, 1936

4 Claims. (Cl. 285—199)

This invention relates to an air conduit for vacuum cleaners or the like and more particularly to a rigid wand of the type which forms a handle for a nozzle or other cleaning implement and connects the same to a suction hose.

An object of the invention is to provide a novel and improved wand of the above type.

Another object is to provide a wand which is adjustable in length to suit the convenience of the operator.

Another object is to provide a wand of the above type which can be locked in any adjusted position.

Another object is to provide a novel and improved locking mechanism for the above purpose.

Other objects and advantages will be apparent as the nature of the invention is more fully disclosed.

Although the novel features which are believed to be characteristic of this invention will be more particularly pointed out in the claims appended hereto, the broader aspects of the invention will be better understood by referring to the following description, taken in connection with the accompanying drawings, in which certain embodiments of the invention are set forth for purposes of illustration.

In the drawings:

Fig. 1 is a side elevation of a vacuum cleaner having a wand constructed in accordance with the present invention;

Fig. 2 is a broken side elevation, partly in section, showing the wand with the parts fully telescoped;

Fig. 3 is a similar view showing the parts extended;

Fig. 4 is a detail view of one form of locking device;

Fig. 5 is a transverse section taken on the line 5—5 of Fig. 4;

Fig. 6 is a detail view of a different form of locking device illustrating another embodiment of the invention;

Fig. 7 is a transverse section taken along the line 7—7 of Fig. 6;

Fig. 8 is a perspective view of the locking saddle shown in Figs. 6 and 7;

Fig. 9 is a detail view of another form of locking device; and

Fig. 10 is a transverse section taken along the line 10—10 of Fig. 9.

In the following description and in the claims, certain specific terms are used for convenience in referring to various details of the invention.

It is to be understood, however, that these terms are to be given as broad an interpretation as the state of the art will permit.

Referring to the drawings more in detail, Fig. 1 shows a vacuum cleaner 10 of standard construction having a suction hose 11 connected thereto and attached to an air conducting handle or wand 12 embodying the present invention. A suction nozzle 13 is connected to the wand 12 in the usual manner.

The wand 12 is formed of two tubular telescoping members 14 and 15 which are arranged so that the member 14 telescopes within the member 15. On the free end of the member 14 there is rigidly attached a connector sleeve 16 which is adapted to receive the nozzle 13. To the opposite end of the member 14 is secured a sleeve 17 having an outwardly extending radial flange 18 which rests against the end of the member 14 for positioning the sleeve 17 thereon and which extends slightly beyond the outer surface of said member to provide a stop in the manner to be described.

The sleeve 17 is also provided with radial flanges 19 and 20 which are spaced to form an annular channel 21 therebetween in which packing material 23 is held. This packing material is preferably made of soft or elastic material, such as felt, leather or the like and forms a sliding fit with the inner surface of the member 15.

A sleeve 24 is attached to the free end of the member 15 and is provided with a radial flange 25 which seats over the end of the member 15 and projects inwardly to engage the flange 20 of the sleeve 17 for limiting the telescoping movement of the members 14 and 15. The sleeve 24 is extended beyond the flange 25 to form a tubular connecting member 26 which is adapted to be connected to the hose 11. This connecting member 26 is preferably made somewhat resilient so as to securely but detachably engage said hose.

The other end of the member 15 carries a sleeve 30 which is similar in form to the sleeve 17 above mentioned and is provided with a radial flange 31 forming a shoulder which seats against the end of the member 15 and extends inwardly past the surface of said member to engage the flange 18 of the sleeve 17 for limiting the extension of the members 14 and 15 as illustrated in Fig. 3. The sleeve 30 is also provided with radial flanges 32 and 33 which are spaced to form an annular channel 34 therebetween in which packing material 35 is held. This packing material is similar to the packing material 23 above mentioned and provides a sliding fit with the outer surface of the member 14.

It is to be understood that the members 14 and 15 are made of any rigid material, such as metal, synthetic resin or other molding composition and that the sleeves above mentioned are rigidly secured thereto in any convenient manner.

In order to lock the members 14 and 15 in any adjusted position a suitable means is provided for clamping the packing material 35 against the outer surface of the member 14. In the embodiment shown in Figs. 2 to 5, this is accomplished by forming a plurality of spaced flexible tongues 36 in the sleeve 30 in engagement with the packing material 35. These tongues 36 are provided with outwardly extending projections or bosses 37 for the purpose to be described.

A rotatable locking ring 40 is positioned around the sleeve 30 and is provided at its ends with inturned flanges 41 and 42 which extend over the flanges 32 and 33, respectively, for holding the ring 40 in position on the sleeve 30. The ring 40 is provided with a plurality of spaced depressions or recesses 43 which correspond in position to the projections 37 on the tongues 36 and are arranged to provide clearance for said projections when they are positioned in alignment therewith. When the ring 40 is rotated, however, its inner surface engages the projections 37 to depress the same and thereby flexes the tongues 36 inwardly and causes the tongues to clamp the packing material 35 against the outer surface of the member 14.

In the operation of the above described device, the ring 40 is positioned to bring the recesses 43 into alignment with the projections 37 of the tongues 36 so as to release the members 14 and 15 for relative telescoping movement. After suitable adjustment of these members has been made, the members are locked in adjusted position by rotating the ring 40 slightly so as to depress the tongues 36 and clamp the packing material 35 against outer surface of the member 14 as above described. In the form shown, the member 14 is sufficiently long to extend beyond the member 15 when the members are in fully telescoped position so as to provide a grip for the operator to be used in adjusting the members.

In the embodiment shown in Figs. 6 and 7 the members 14 and 15 and the sleeves 17 and 30 are arranged in the manner set forth above. In this embodiment, however, the tongues 36 in the end of the sleeve 30 are omitted and a semi-circular saddle 45 is loosely mounted between the packing material 35 and the sleeve 30. This saddle is provided with a projection 46 which extends through a suitable aperture 47 in the sleeve 30. A locking ring 48 is positioned over the sleeve 30 and is provided with inturned flanges 49 and 50 extending over the flanges 32 and 33 of said sleeve 30 to secure the ring 48 in position thereon. The ring 48 is provided with an outwardly extending portion 51 terminating in a shoulder 52 and having a cam surface which is adapted to depress the projection 46 of the saddle 45 when the ring 48 is rotated.

In this embodiment the members 14 and 15 are locked in any adjusted position by rotating the ring 48 in a clockwise direction, as viewed in Fig. 7, so as to cause the cam surface of portion 51 to engage the projection 46 and depress the saddle 45, thereby clamping the packing material 35 against the outer surface of the member 14. For releasing the members, the sleeve 48 is rotated in a counter-clockwise direction until the shoulder 52 engages the projection 46 as

shown in Fig. 7. In this position the cam surface of portion 51 provides clearance for the projection 46 and releases the pressure on the saddle 45. In the form shown in Figs. 6 and 7, a single saddle 45 and projection 46 are used. It is to be understood, however, that two or more such locking devices may be distributed around the periphery of the packing material if desired.

In the embodiment shown in Figs. 9 and 10, the various parts are similar to those described above with the exception of the sleeve 30. In this embodiment the sleeve 30 is provided with a peripheral groove 56 of substantial width for the purpose to be described and is provided with a conical end portion 58 beyond the radial groove 56. A locking ring 59 extends over the conical end 58 of the sleeve 30 and is provided with an inturned flange 60 which engages and slides in the radial groove 56. The outer end of the locking ring 59 is provided with an inturned flange 61 and with an inner conical member 62 having a shoulder 63 and a flange 64 which are spaced to receive and hold packing material 35. The conical member 62 is provided with a plurality of spaced axial slits 65 between which resilient tongues 66 are formed. The conical member 62 and the conical section 58 of the sleeve 30 are arranged so that axial movement of the conical member 62 causes pressure to be exerted by the conical section 58 which depresses the tongues 66 and clamps the packing material 35 against the outer surface of the member 14.

In this embodiment the members are clamped in any desired position or are released by causing the axial movement of the locking ring 59. In order to facilitate the operation of this ring, the surface thereof may be fluted as indicated in Fig. 9 or may be otherwise formed with means to provide a grip for the operator.

While the wand 12 has been shown as formed of two telescoping sections, it is obvious that the invention is not restricted thereto, but that any desired number of sections may be provided. Although certain specific embodiments have been shown for purposes of illustration, it is to be understood that the invention is not to be limited thereto, but that various changes and substitutions may be made therein as will be apparent to a person skilled in the art. The invention is to be limited only in accordance with the following claims when interpreted in view of the prior art.

What I claim is:

1. A wand for vacuum cleaners and the like having a suction hose and a cleaning nozzle, comprising a pair of telescoping members adapted to be connected respectively to said hose and said nozzle, one of said members carrying flexible fingers adapted to exert controlled pressure on the other of said members, a locking ring axially slidable on said first mentioned member, said locking ring having a tapered surface to engage said fingers to cause the same to frictionally lock the members in any extended position.

2. A wand for vacuum cleaners and the like having a suction hose and a cleaning nozzle, comprising a pair of telescoping members adapted to be connected respectively to said hose and said nozzle, a sleeve carried by one of said members, soft packing material held in said sleeve in sliding engagement with the other of said members, a movable member engaging said packing material and a locking ring movably mounted on the exterior of the outer telescoping member.

and movable to cause said movable member to clamp said packing against said other member for locking the same in any extended position.

3. A wand for vacuum cleaners and the like including a pair of substantially rigid hollow cylindrical imperforate fluid conveying telescoping members, a clamping member carried by the outer of said telescoping members including an arcuate member formed with a radially outwardly extending projection, and a sleeve rotatably secured to said outer member, said sleeve having an internal cam surface cooperating with said projection to force said arcuate member into clamping relationship with the inner of said telescoping members upon rotation of said sleeve, whereby said telescoping members are locked together.

4. A wand for vacuum cleaners and the like including a pair of substantially rigid hollow cylindrical imperforate fluid conveying telescoping members, a clamping member carried by the outer of said telescoping members including an arcuate member formed with a radially outwardly extending projection, a packing ring between the arcuate member and the inner of said telescoping members, and a sleeve rotatably secured to said outer member, said sleeve having an internal cam surface cooperating with said projection to displace said arcuate member so as to clamp said packing against said inner member, whereby said telescoping members are locked together.

AXEL ALBERT FORSBERG.
